UNITED STATES PATENT OFFICE.

CHARLES A. FRAZER, OF WESTPORT, CONNECTICUT.

DESIGN FOR A SMOKING-TABLE.

44,441.

Specification for Design.

Patented Aug. 5, 1913.

Application filed March 15, 1913. Serial No. 754,639. Term of patent 7 years.

To all whom it may concern:

Be it known that I, CHARLES A. FRAZER, a citizen of the United States, residing at Westport, in the county of Fairfield and State of Connecticut, have invented a new, original, and ornamental Design for a Smoking-Table, of which the following is a specification, reference being had to the accompanying drawings, forming part thereof.

The figure is a view of a smoking table showing my new design.

I claim:—

The ornamental design for a smoking table, as shown.

CHARLES A. FRAZER.
